(57) **CLAIM**

The ornamental design for a suspension tie-plate, as shown and described.

DESCRIPTION

FIG. 1 is a perspective view showing the top, from, and right sides of a suspension tie-plate having the inventive design; FIG. 2 is a front elevational view of the suspension tie-plate shown in FIG. 1;

FIG. 3 is a rear elevational view of the suspension tie-plate shown in FIG. 1, wherein the front elevational view of FIG. 2 is identical to the rear elevational view of FIG. 3;

FIG. 4 is a top plan view of the suspension tie-plate shown in FIG. 1;

FIG. 5 is a bottom plan view of the suspension tie-plate shown in FIG. 1, wherein the top plan view of FIG. 4 is identical to the bottom plan view of FIG. 5;

FIG. 6 is a left side elevational view of the suspension tie-plate shown in FIG. 1; and,

FIG. 7 is a right side elevational view of the suspension tie-plate shown in FIG. 1, wherein the left side elevational view of FIG. 6 is identical to the right side elevational view of FIG. 7.
